RECEIVING APPARATUS FOR TELEVISION

René Barthelemy, Fontenay aux Roses, France,
assignor to Compagnie pour la Fabrication des
Compteurs et Materiel d'Usines a Gaz, Mont-
rouge, France

Application December 16, 1931, Serial No. 581,395
In France December 20, 1930

3 Claims. (Cl. 178—6)

It has already been proposed for a long time to use a Crookes tube mounted in the form of a cathode oscillograph to reproduce scenes by means of television, telecinematography etc., but one difficulty which has held up the application of these devices is the insufficiency of the light produced by the moving cathode spot on the fluorescent surface which forms the screen.

The present invention has for its object to provide an apparatus in which the moving luminous source will be considerably more intense and in which a cathode ray oscillograph is used in order to cause the movable light source to traverse the screen on which the image or scene produced is observed.

To this end, the beam of cathode rays in the oscillograph is used as a moving conductor to connect, at a great speed, an electric source to a number of points disposed on the interior of the oscillograph, each of these points being electrically connected with the cathode of a tube containing a rare gas maintained at a low pressure. In this manner the electric discharge set up successively between each one of the cathodes and the anode of the rarefied gas tube renders each of the cathodes successively luminous with an intensity proportional to that of the cathode ray beam, and by causing the intensity of the directing fields of the oscillograph to vary in synchronism with the transmission to be received, one can obtain the synthesis of the image or scene to be reproduced.

The system will thus comprise a cathode ray tube set up as an oscillograph and provided with means for modulating the cathode ray beam according to the variations of current produced in the receiver by the received transmissions; a tube of rarefied rare gas containing a large number of cathodes having extremities or prolongations which project into the interior of a cathode ray tube and form a surface swept by the cathode ray beam, the anode of the said rarefied gas tube being disposed in such a manner that it does not obstruct the view of the cathodes, and the source producing the electric discharges between said anode and successive cathodes having such a voltage that the intensity and desired luminous effects are obtained.

The attached drawing shows by way of example and not of limitation, one embodiment of the system in which the rare gas tube is contiguous to the oscillograph.

Figure 1 is a plan view and

Figure 2 is an end view of the arrangement.

As shown in Figure 1, 1 is the cathode ray tube,

2 is the rarefied gas tube juxtaposed to the oscillograph 1. The oscillograph 1 comprises a cathode 3 and an anode 4. This anode is provided with an opening through which passes the cathode ray beam emitted by the cathode 3. The directing fields of the oscillograph are here shown as two rectangularly disposed electro-static fields produced by the two condensers 5 and 6 between which passes the cathode ray beam, which is thus deviated. This beam sweeps the surface 7 of the wall 9 which separates the cathode ray tube 1 from the rarefied gas tube 2. Said wall 9 is constructed very thin and consists of electrically semi-conducting material. The surface 10 of the wall 9, which is disposed in the rarefied gas tube 15 2, represents the screen on which the reproduced scene or image will appear. Thus, a luminous spot will appear inside the tube 2 on the surface 10 of the wall 9 opposite the point of impact of the cathode ray beam on the surface 7 in tube 1. 20 This tube is also provided with an anode 11 disposed peripherally with respect to the screen surface 10 in order that it shall not obstruct the view of the surface (Figure 2).

The gas contained in the interior of the tube 25 2 may be, for example, helium or neon or a mixture of these gases. The pressure in the interior of the tube 2 depends upon the nature of the gas and is such that the discharge produces only luminosity of the cathodes. 30

The electric discharge between the anode 11 and the various cathodes constituting the surface 10 is produced by an electric source 12 the voltage of which is such that the desired luminosity of the said cathode is obtained. The source 12 is 35 connected on one hand to the anode 11 and on the other hand to the cathode 3 of the cathode ray tube, the cathode ray beam thereby serving as a moving conductor to connect the source 12 successively to the various cathodes of the tube 2. 40

The brilliancy of the luminous spot covering the said cathodes depends upon the intensity of the discharge current. This intensity in turn depends upon the resistance to the passage of the current offered by the cathode ray beam, that 45 is to say, on the intensity of the said beam. Thus, the variations of brilliancy of the cathodes of the tubes necessary for the synthesis of the images or scenes to be reproduced will be obtained by modulating the intensity of the cathode ray beam according to the variations of the current produced at the receiver by the transmission to be received. In the example shown in Figure 1 this modulation is obtained by interposing in the circuit of the anode 4 the secondary of a transformer 13, 50 55

the primary of which is traversed by the current set up at the receiver by the transmission to be received. There are thus produced voltage variations resulting in corresponding variations in the 5 intensity of the cathode ray beam.

The voltages applied to the terminals of the condensers 5 and 6 are such that the cathode ray beam sweeps the surface 7 in parallel juxtaposed bands, in synchronism with the transmitter.

10 Magnetic fields could be employed equally well.

The embodiment shown in Figure 1 is not intended to be in any way limitative of this invention. The two tubes 1 and 2 may equally well be separated and the cathodes of the tube 2 suitably connected to the different points of the surface 7 in the tube 1.

What I claim is:

1. In an apparatus for reproducing images and scenes by television and telecinematography 20 formed by a cathode ray tube and a luminescent electric discharge tube forming a continuation of the first mentioned tube, a thin partition of semi-conducting material separating said tubes, one face of said partition being impinged by the cathode rays and the other forming the cathodic surface of the luminescent tube and the screen on which the reproduced image is observed, a metallic piece within the luminescent tube and constituting the anode thereof perpendicular to the 25 mean direction of the cathode rays, said metallic piece having an opening through which the entire cathodic surface may be observed, a source of electric voltage directly connected by conducting 30

wires to said anode of the luminescent tube and to the cathode of the cathode ray tube, and a transformer in the primary of which flows the received current, the secondary being connected in series in cathode-anode circuit of the cathode 5 ray tube.

2. In an apparatus as claimed in claim 1, in which the said luminescent tube contains an inert gas.

3. In an apparatus for reproducing images and 10 scenes by television and telecinematography formed by a cathode ray tube and a luminescent electric discharge tube forming a continuation of the first mentioned tube, a thin partition of semi-conducting material separating said tubes, one 15 face of said partition being impinged by said cathode rays and the other forming the cathodic surface of the luminescent tube and the screen on which the reproduced image is observed, a tubular anode within the luminescent tube, the axis of 20 said tubular anode being parallel with the mean direction of the cathode rays, the entire cathodic surface being observable through said tubular anode, a source of electric voltage directly connected by conducting wires to said tubular anode 25 of the luminescent tube and to the cathode of the cathode ray tube, and a transformer in the primary of which flows the received current, the secondary being connected in series in the cathode-anode circuit of the cathode ray tube. 30
